Inventor
Charles M. Wills

By his Attorney

Frank J. Neuman

UNITED STATES PATENT OFFICE.

CHARLES M. WILLS, OF ATLANTIC CITY, NEW JERSEY, ASSIGNOR TO THE AMERICAN TRANSOM CO., INC., OF PHILADELPHIA, PENNSYLVANIA, A CORPORATION OF PENNSYLVANIA.

VISIONLESS VENTILATOR.

Application filed March 31, 1923. Serial No. 266,261.

My invention relates to ventilators and refers particularly to ventilators through which vision is always prevented and through which the passage of air may be allowed or prevented.

It is usually desirable that ventilators, particularly those adapted for door transoms be of such construction that while the free passage of air therethrough may be allowed and prevented as desired, the passage of light and vision should be impossible at all times.

The device of my invention accomplishes these desirable objects in a most effective and simple manner.

In the accompanying drawings illustrating one form of the device of my invention similar parts are designated by similar numerals.

20 Figure 1 is a door with my device installed as a transom.

Figure 2 is a vertical section of my device in closed position taken through the line 2-2 of Figure 3.

25 Figure 3 is a section taken through the line 3-3 of Figure 2.

Figure 4 is an enlarged view of a portion of Figure 3 with the device in open position.

30 The particular form of my device shown in the accompanying drawings comprises a casing having the channel shaped top 10, bottom 11, ends 12, 12 and sides 13, 13.

A plurality of inturned wings 14, 14, form 35 a plurality of vertical openings in the sides 13, 13, the openings in the two sides being opposite each other.

Between opposite openings in the sides 13, 13, and capable of abutment upon the opening wing 14, 14 of one side is a shutter 15, pivotally carried by the pivots 16, 16.

Each shutter 15 is pivotally attached to the longitudinal rod 17 by the link 18, fixedly attached to the shutter 15 at 19.

45 One end of the rod 17 carries a pin 21 movable within the slot 22 of the bent arm 23 revoluble upon the fixed shaft 24. The arm 23 carries the handle 25.

When the device is in the position shown 50 in Figure 4, air may pass through the device as indicated by the arrows.

When the handle 25 is moved into the position shown in Figure 3, each shutter abuts

upon a pair of wings, preventing the passage of air through the device. 55

It will be noted that vision through the device is prevented at all times.

My device, therefore, presents a visionless ventilator through which the passage of air may be allowed or prevented by simple 60 and effective means.

I do not limit myself to the particular size, shape, number or arrangement of parts as shown and described, as these are given simply as a means for clearly describing the device of my invention. 65

What I claim is:

1. In a visionless ventilator, in combination, a casing having a top, a bottom, two ends and two sides, each side having a plurality of vertical openings, the openings in the two sides being in opposite alignment with each other; a wing extending inwardly from each side margin of each opening; a pivotal shutter positioned between each pair of opposite openings and capable of abutment with the wings adjacent to one opening and means exterior of the device whereby the shutters may be moved into abutment and non-abutment with said adjacent wings. 75

2. In a visionless ventilator, in combination, a casing having a top, a bottom, two ends and two sides, each side having a plurality of vertical openings, the openings in the two sides being in opposite alignment with each other; a wing extending inwardly from each side margin of each opening; a pivotal shutter positioned between each pair of opposite openings and capable of abutment with the wings adjacent to one opening, 80

a longitudinally positioned rod and means whereby the movements of the rod will cause the shutters to move into abutment and non-abutment with said adjacent wings. 85

3. In a visionless ventilator, in combination, a casing having a top, a bottom, two ends and two sides, each side having a plurality of vertical openings, the openings in the two sides being in opposite alignment with each other; a wing extending inwardly from each side margin of each opening; a pivotal shutter positioned between each pair of opposite openings and capable of abutment with the wings adjacent to one opening, 90

a longitudinally positioned rod, a pivotal 95

arm movably connected with said rod and extending outwardly of the device, the movements of the arm causing the shutters to move into abutment and non-abutment with 5 said adjacent wings.

4. In a visionless ventilator, in combination, a casing having a top, a bottom, two ends and two sides, each side having a plurality of vertical openings, the openings in 10 the two sides being in opposite alignment with each other; a wing extending inwardly from each side margin of each opening; a pivotal shutter positioned between each pair of opposite openings and capable of 15 abutment with the wings adjacent to one opening, a longitudinally positioned rod, a pivotal arm extending outwardly of the device and having a slot in its inner portion, a pin carried by the rod and movable within 20 said slot, the movements of the arm causing the shutters to move into abutment and non-abutment with said adjacent wings.

5. In a visionless ventilator, in combina-

tion, a casing having a top, a bottom, two ends and two sides, each side having a plurality of vertical openings, the openings in the two sides being in opposite alignment with each other; a wing extending inwardly from each side margin of each opening; a pivotal shutter positioned between each pair of opposite openings and capable of abutment with the wings adjacent to one opening, a longitudinally positioned rod, a pivotal link connecting each said shutter with 25 said rod, a pivotal arm extending outwardly 30 of the device and having a slot in its inner portion, a pin carried by the rod and movable within said slot, the movements of the arm causing the shutters to move into abutment and non-abutment with said adjacent 35 wings.

Signed at Philadelphia, in the county of Philadelphia and State of Pennsylvania, this 29th day of March, 1928.

CHARLES M. WILLS.
